UNITED STATES PATENT OFFICE.

MEYER L. ROBBINS, OF NEW YORK, N. Y.

DESIGN FOR AN EXPANSIBLE CHAIN.

43,941.

Specification for Design.

Patented Apr. 29, 1913.

Application filed February 12, 1913. Serial No. 747,995. Term of patent 7 years.

To all whom it may concern:

Be it known that I, MEYER L. ROBBINS, a citizen of the United States, residing at New York city, in the county of New York and State of New York, have invented a new, original, and ornamental Design for an Expansible Chain, of which the following is a specification, reference being had to the accompanying drawing, forming part thereof.

Figure 1 is a plan view and Fig. 2 a side view of an expansible chain, showing my new design.

I claim:

The ornamental design for an expansible chain, as shown.

MEYER L. ROBBINS.

Witnesses:

FREDK. F. SCHUETZ,
LAURA E. SMITH.
